UNITED STATES PATENT OFFICE.

THOMAS PITBLADDO, OF BROOKLYN, NEW YORK.

DESIGN FOR CEMETERY-FENCES.

Specification forming part of Design No. 6,762, dated July 8, 1873; application filed April 26, 1873

To all whom it may concern:

Be it known that I, THOMAS PITBLADDO, of Brooklyn, in the county of Kings and State of New York, have invented a new and original Design for Cemetery-Fence, of which the following is a specification:

The nature of my design is fully represented in the accompanying photographic illustration, to which reference is made.

a is the stone coping, resting on stone posts *b* and on stone pillars *c* at one end. The other

pillar, *d*, and the coping are one. *e* represents the "stoop," consisting of the pillars *f*, steps *g*, side buttresses *h*.

The form of this fence is usually circular or oval; but it may be square or rectangular.

I claim as my invention—
The design for a cemetery-fence, as shown.

THOMAS PITBLADDO.
